UNITED STATES PATENT OFFICE.

ALANSON P. BRUSH, OF DETROIT, MICHIGAN.

JACKETING SYSTEM FOR ENGINE-CYLINDERS.

No. 841,846.

Specification of Letters Patent.

Patented Jan. 22, 1907.

Application filed December 15, 1902, Serial No. 135,205.

To all whom it may concern:

Be it known that I, ALANSON P. BRUSH, a citizen of the United States, residing at Detroit, county of Wayne, State of Michigan, have invented a certain new and useful Improvement in Jacketing Systems for Engine-Cylinders, of which the following is a specification, reference being had to the accompanying drawings, which form a part of this specification.

My invention has for its object certain new and useful improvements in the construction of engines, and relates more particularly to the construction of internal-combustion engines, the specific objects of my invention pertaining more especially to the provision of a water-jacket wall for the engine cylinder or cylinders in connection with related parts of the engine.

I carry out my invention as hereinafter described and claimed, and illustrated in the accompanying drawings, in which—

Figure 1 is a view of the water-jacket and cylinder, parts being in section. Fig. 2 is a similar view, but showing various parts before they are assembled. Fig. 3 is an end view of the cylinder. Fig. 4 is an enlarged view in section of a cylinder and its adjacent water-jacket wall.

As regards the water-jacket wall, my invention is designed to provide an engine-cylinder with a jacket-wall of superior construction, efficiency, and durability, the water-jacket wall at the same time forming its own gasket at the end thereof toward the open end of the cylinder and between the cylinder and the adjacent valve-chamber at the opposite end of the cylinder.

I carry out my invention as follows:

In the drawings, *a* represents the frame of an engine, and *b* an engine-cylinder.

A valve-chamber is indicated at *c*.

My invention is intended to be applied to either a single or multiple cylinder engine, as may be desired.

My improved water-jacket wall is intended to be made of thin soft metal, the same being constructed at the end thereof adjacent to the frame of the engine with an outwardly-turned flange, (indicated at *g*.) At its opposite end the jacket-wall is formed with an inwardly-turned flange, (indicated at *h*.) the wall being spaced from the engine-cylinder to form a water-chamber therebetween, (indicated at *i*.) The cylinder of the engine

is formed with a discharge-channel *j*, communicating with the water-chamber *i* at one end thereof and at the other extremity with one or more inlet-channels *k*, communicating with said water-chamber. The cylinder is formed with an outwardly-projecting flange (indicated at *l*) at one end thereof, against which the outwardly-turned flange *g* of the jacket-wall seats. To clamp the flange *g* of jacket-wall upon the flange *l* of the cylinder, I employ a clamping-ring *m*, said ring being held in place to clamp the flange *g* of the jacket-wall between it and the flange *l* of the cylinder in any suitable manner.

In the drawings I have shown the frame of the engine provided with a series of studs, (indicated at *n*.) said studs passed through the clamping-ring and held in engagement therewith by nuts *p*. It will be obvious that the ring *m* thus, together with the studs *n* and the nuts *p*, not only clamp the flange *g* of the jacket-wall between said ring and the flange *l*, but at the same time they unite the end of the cylinder with the frame of the engine. The flange *g* of the jacket-wall being made of soft metal, it is obvious, serves as a gasket, as already indicated. The inwardly-turned flange *h* at the opposite end of the jacket-wall is held in place between the adjacent end of the cylinder and the adjacent end of the wall of the valve-chamber *c*. The engine-cylinder is preferably constructed with an inwardly-turned flange, as shown, at the end thereof adjacent to the valve-chamber, the inwardly-turned flange of the water-jacket being clamped between the water-jacketed valve-chamber and the inwardly-turned flange on the adjacent end of the cylinder.

The valve-chamber *c* may be united with the adjacent end of the cylinder by means of a threaded nipple, (indicated at *q*.) said nipple formed with right and left hand screw-threads on opposite ends thereof to engage the correspondingly-threaded ends of the cylinder and of the chamber *c*. This nipple may be of any suitable form for the ready engagement of a suitable tool therewith to engage the nipple with the adjacent parts. The jacket-wall so formed allows, if desired, expansion and contraction. I prefer that the head of the cylinder shall be cast upon the cylinder. The flange *l* of the cylinder is cored out to permit the water to pass from the chamber *i* into the outlet-channel *j*, as indicated at *r*. So, also, the walls of the

valve-chamber *c* are cored out, as indicated, for example, at *s*, to allow the water to pass into the chamber *i*, the valve-chamber *c* being provided with a water-chamber *t*, into which water is admitted in any desired manner:

The frame of the engine is formed with a flange *w*, with which the studs *n* are engaged. It will be perceived that the water-jacket wall at its end toward the valve-chamber *c* is preferably bent on an arc of a circle and that the flange *h* is of a length sufficient to allow for expansion and contraction or for inequalities of lengths due either to inaccuracies of construction or differences of expansion and contraction. Obviously the flange *h* of the jacket-wall, being made of thin and soft metal, will readily yield to allow for any such inequalities or differences. I do not, however, limit myself to the turning of a flange on an arc of a circle.

It will be seen that in the construction shown and described the end of the cylinder is formed with a longitudinal extension on the end thereof adjacent to the valve-chamber, the extension being provided with water-passages opening into the water-chamber around the cylinder and into the water-chamber around the valve-chamber.

30. What I claim as my invention is—

1. The combination with an engine provided with a cylinder and a valve-chamber of a water-jacket wall having flanges at its opposite extremities forming a water-chamber between the jacket-wall and the cylinder, one end of the cylinder formed with a flange against which the flange of the corresponding end of the jacket-wall seats, means to secure the corresponding flange upon its seat on the flange of the cylinder, the flange at the opposite end of the jacket-wall seating against the head of the cylinder, and separate means to clamp the adjacent flange of the jacket-wall upon the end of the cylinder, said cylinder flange provided with a channel communicating with the water-chamber and the end of the cylinder provided with channels communicating with the water-chamber.

2. The combination with an engine provided with a frame, a cylinder, and a valve-chamber of a water-jacket wall constructed with a flange at one end and clamped between the end of the cylinder and the valve-chamber, and forming a water-chamber between the jacket-wall and the cylinder, the opposite end of the water-jacket wall formed with a flange seating against the adjacent end of the cylinder, a separate clamping-ring to clamp the adjacent flange of the jacket-wall against the adjacent end of the cylinder, the frame of the engine provided with means to clamp the said ring in place and to engage the adjacent end of the cylinder with the engine-frame.

65. 3. The combination with an engine pro-

vided with a frame, a cylinder and a valve-chamber of a water-jacket wall flanged at its opposite extremities, the flange at one extremity of the jacket-wall clamped between the valve-chamber and the end of the cylinder, a ring to clamp the flange on the opposite end of the jacket-wall between the ring and the adjacent end of the cylinder, and means to secure the ring, the jacket-wall and the cylinder upon the frame of the engine, the means for engaging the flanges at the opposite ends of the jacket-wall being independent one of another.

4. The combination with an engine and its cylinder of a metal water-jacket wall provided with flanges at its opposite extremities and means to engage said flanges and hold the jacket-wall in place, one of said flanges being of a length sufficient to yield and allow for inequalities of lengths due either to inaccuracies of construction or differences of expansion and contraction, the means for engaging the flanges at the opposite ends of the jacket-wall being independent one of another.

5. The combination with an engine provided with a frame, a cylinder provided with an outwardly-projecting flange toward one end thereof, and with a valve-chamber, of a water-jacket wall constructed with a flange at one end and clamped between the end of the cylinder and the valve-chamber, and forming a water-chamber between the jacket-wall and the cylinder, the opposite end of the jacket-wall formed with a flange seating against the adjacent flange on the cylinder, a separate clamping-ring to clamp the adjacent flange of the jacket-wall against the adjacent flange of the cylinder, the frame of the engine provided with means to clamp the said ring in place, and to engage the adjacent end of the cylinder with the engine-frame, the means used to clamp the outwardly-turned flange of the water-jacket to the flange on the cylinder simultaneously clamping the cylinder to the frame of the engine.

6. The combination with an engine provided with a frame, a cylinder provided with an outwardly-projecting flange toward one end thereof, and a valve-chamber, of a water-jacket wall constructed with a flange at one end and clamped between the end of the cylinder and the valve-chamber and forming a water-chamber between the jacket-wall and the cylinder, the opposite end of the water-jacket wall formed with a flange seating against the adjacent flange of the cylinder, a separate clamping-ring to clamp the adjacent flange of the jacket-wall against the adjacent flange of the cylinder, the frame of the engine provided with means to clamp the said ring in place and to engage the adjacent end of the cylinder with the engine-frame, the means which clamp the

inwardly-turned end of the water-jacket to the cylinder simultaneously clamping the valve-chamber to the cylinder.

7. The combination of an engine provided with a frame, with a cylinder provided with an outwardly-extending flange toward one end thereof, and with a valve-chamber, of a water-jacket wall oppositely flanged at its extremities, the flange at one extremity of the jacket-wall clamped between the valve-chamber and the end of the cylinder, and a separate ring exterior to the jacket-wall to clasp the flange on the opposite end of the jacket-wall upon the adjacent flange of the cylinder.

8. In an engine of the described class, a water-jacket consisting of sheet metal, an inwardly-turned portion at one end of the jacket which forms a gasket between the cylinder and the cylinder-head, a ring upon the cylinder at the opposite end of the water-jacket and means for securing the ring and the extremity of the water-jacket hermetically in fixed relation.

9. The combination with an engine and its cylinder, of a water-jacketed valve-chamber, a water-jacket forming a water-chamber about the cylinder and having an inwardly-turned flange at one end of the jacket forming a gasket between the end of the cylinder and the valve-chamber, said gasket provided with water-passages through which the water-jacket of the valve-chamber communicates with the water-chamber about the cylinder, and means to seal the other end of the water-jacket upon the cylinder.

10. The combination with an engine and its cylinder of a water-jacketed valve-cham-

ber, and a flexible sheet-metal water-jacket forming a water-chamber about the cylinder and having an inwardly-turned flange at one end of the jacket forming a gasket between the end of the cylinder and the valve-chamber, said flange having water-passages therethrough whereby the water-chamber about the valve-chamber communicates with the water-chamber about the cylinder, said flange forming a gasket both outside and inside of the water-passage therethrough.

11. In an engine of the described class the combination of a cylinder, a water-jacketed valve-chamber, a water-jacket for the engine-cylinder consisting of flexible sheet metal having an inwardly-turned flange at one end of the jacket which forms a gasket between the ends of the cylinder and the valve-chamber, and means to hermetically seal the other end of the water-jacket to the cylinder, a portion of said flange extending outside the adjacent ends of the valve-chamber and the cylinder to allow for contraction and expansion of the jacket.

12. The combination, with the cylinder and its head having aligned apertures, of a ring arranged in said apertures, positively engaging one of said parts to prevent withdrawal and threaded into the other part to clamp the two parts together.

In testimony whereof I have signed this specification in the presence of two subscribing witnesses.

ALANSON P. BRUSH.
